UNITED STATES PATENT OFFICE.

KATHARIN ELIZA LANDAU, OF NEW YORK, N. Y.

IRONING-MACHINE.

SPECIFICATION forming part of Letters Patent No. 610,942, dated September 20, 1898.
Application filed August 13, 1897. Serial No. 648,127. (No model.)

To all whom it may concern:

Be it known that I, KATHARIN ELIZA LANDAU, a citizen of the United States, residing at New York, in the county of New York and 5 State of New York, have invented certain new and useful Improvements in Ironing-Machines, of which the following is a full and complete specification, such as will enable those skilled in the art to which it appertains 10 to make and use the same.

This invention relates to ironing-machines; and the object thereof is to provide an improved device of this class which is simple in construction and operation and which may 15 be used in private houses or in laundries and wherever such machines are required.

The invention is fully disclosed in the following specification, of which the accompanying drawings form a part, in which—

20 Figure 1 is a sectional side view of my improved ironing-machine; and Fig. 2, an end view thereof, part of the construction being broken away and part shown in section.

In the drawings forming part of this specification the separate parts of my improvement are designated by the same numerals of reference in each of the views, and in the practice of my invention I provide a machine for the purpose herein specified which consists 25 of a frame composed of ends 5 and a top cross-bar 6, and the ends 5 are preferably composed of angular frames, as shown in Fig. 2, which are provided with upwardly-directed extensions 7, with which the top cross-bar 6 is connected.

30 Mounted in the bottom of the end frames is a treadle-plate 8, with which is connected a treadle-rod 9, which is connected with a crank 10, formed on or secured to a shaft 11, which 35 passes centrally through one of the end frames and is provided with a gear-wheel 12 on the outer end thereof.

40 Mounted centrally of the top of the main portion of the end frames 5 is a hollow roller 45 13, which is provided at each end with a tubular hub 14, and said tubular hubs project through the end frames, and one of said hubs is provided with a gear-wheel 15, which operates in connection with the gear-wheel 12 on 50 the crank-shaft 11, and passing through said tubular hubs and through said hollow roller 13 is a gas-burner tube 16, provided with

burner-tips 17, any desired number of which may be employed, and one end of said burner-tube is provided with a flexible tube 18, by 55 which gas is supplied thereto, and the opposite end of said burner-tube is mounted in and secured in a bracket 19, secured to the adjacent end frame, by means of which said burner-tube is prevented from turning, and 60 said end of said burner-tube is also provided with a flexible tube 20.

The roller 13 is provided at one end with a small opening 21, through which a lighting device may be inserted, and formed in the 65 upwardly-directed extensions 7 of the end frames 5 are vertical slots 22, and mounted on and adapted to bear on the roller 13 is a pressing-iron 23, which is provided at each end with projections 24, which pass through said 70 slots and which are angular in cross-section, and secured to each of said projections is a contractile spiral spring 25, the lower ends of which are secured to the end frames, and these springs are designed to pull said pressing-iron 23 downwardly, so that it will bear 75 upon the roller or upon the article being ironed in the operation of the machine, as hereinafter described.

The pressing-iron 23 is circular in cross-section and of the same length as the roller and is also hollow, and one side thereof projects downwardly and backwardly over the roller 13, and one of said projections 24 is provided with a longitudinal opening through which is passed a burner-tube 26, provided with burner-tips 27, and one end of the flexible tube 20 is connected with the outer end of the burner-tube 26, and the pressing-iron 23 is also provided at one end with a small opening 28, through which a lighting device may 90 be inserted.

Connected with the upper end of the pressing-iron 23 and centrally thereof is a chain or cord 29, one end of which is connected with 95 a pulley 30, mounted in the top bar 6 of the frame and centrally thereof, and the shaft 31 of the pulley 30 is provided with a crank 32, and secured to the bar 6 adjacent to said pulley and transversely thereof is a supplemental 100 bar 33, in which is formed a plurality of openings or perforations 34, and the crank 32 is provided with a pin 35, which passes therethrough and which is adapted to be passed

through either of the holes or openings 34 in the supplemental bar 33. The pin 35 is adapted to be removed from both the crank 32 and the bar 33, and by means of this construction the pressing-iron 23 may be raised whenever desired.

The operation will be readily understood from the foregoing description when taken in connection with the accompanying drawings 10 and the following statement thereof.

It will be understood that the gas is supplied to the tube 16 through the pipe 18 and to the pipe 26 through the pipe 20, and the gas may be ignited in the roller 13 and in the 15 pressing-iron 23 whenever desired through the openings 21 and 28. The roller 13 and the pressing-iron 23 are highly heated by the burning gas therein, and in practice the roller 13 is revolved by means of the treadle 8 and 20 the operative devices in connection therewith, including the treadle-rod 9, the shaft 11, the crank 10, and the wheels 12 and 15, and the articles to be ironed are passed between the roller 13 and the pressing-iron 23, and said 25 pressing-iron is held in position by the springs 25 and is adapted to yield sufficiently to allow the articles to pass freely through between the same and the roller 13. The strength of the springs 25 may be adjusted in any desired 30 manner, and other springs may be placed over the projections 24 in the slots or openings 22, and the said pressing-iron may be raised to any desired point and held in any desired position by the crank 32 and the devices connected therewith.

My improved ironing-machine may be employed for ironing all kinds or classes of articles or garments, and my invention is not limited to the means herein described for revolving the roller 13, and any suitable device may be employed for this purpose.

Having fully described my invention, I claim as new and desire to secure by Letters Patent—

45 1. An ironing-machine, comprising a suitable frame, a hollow cylindrical roller mounted therein and provided at each end with tubular hubs, a vertically-movable hollow pressing-iron mounted above said roller and adapted to rest thereon, the under surface of which conforms to the surface of said roller, said pressing-iron being substantially of the same length as said roller, and being also provided at its opposite ends with projections, one of 50 which is tubular in form, springs by which said pressing-iron is depressed into contact with said roller, gas-burner tubes mounted in said pressing-iron and in said roller, and extending longitudinally thereof, the burner- 55 tube in the pressing-iron being projected through one end thereof, and the burner-tube in the roller being projected through both ends thereof, said burner-tubes being in communication at one end, and the burner-tube 60 in the roller being provided with a gas-supply pipe at its opposite end, and means for revolving said roller, and for raising the pressing-iron against the operation of the springs 65 by which it is depressed, consisting of a pulley mounted in said frame above said pressing-iron, a chain mounted thereon and connected with said iron, and a lever connected with the shaft of said pulley and operating in connection with a locking device secured to said frame, substantially as shown and described.

the gas-pipe therein, substantially as shown and described.

2. An ironing-machine, comprising a suitable frame, a hollow cylindrical roller mounted therein and provided at each end with tubular hubs, a vertically-movable hollow pressing-iron mounted above said roller and adapted to rest thereon, the under surface of which 70 conforms to the surface of said roller, said pressing-iron being substantially of the same length as said roller, and being also provided at its opposite ends with projections, one of which is tubular in form, springs by which 75 said pressing-iron is depressed into contact with said roller, gas-burner tubes mounted in said pressing-iron and in said roller, and extending longitudinally thereof, the burner-tube in the pressing-iron being projected 80 through one end thereof, and the burner-tube in the roller being projected through both ends thereof, said burner-tubes being in communication at one end, and the burner-tube in the roller being provided with a gas-supply 85 pipe at its opposite end, and means for revolving said roller, and for raising the pressing-iron against the operation of the springs 90 by which it is depressed, substantially as shown and described. 95

3. An ironing-machine, comprising a suitable frame, a hollow cylindrical roller mounted therein and provided at each end with tubular hubs, a vertically-movable hollow pressing-iron mounted above said roller and adapted to rest thereon, the under surface of which 100 conforms to the surface of said roller, said pressing-iron being substantially of the same length as said roller, and being also provided at its opposite ends with projections, one of which is tubular in form, springs by which 105 said pressing-iron is depressed into contact with said roller, gas-burner tubes mounted in said pressing-iron and in said roller, and extending longitudinally thereof, the burner-tube in the pressing-iron being projected 110 through one end thereof, and the burner-tube in the roller being projected through both ends thereof, said burner-tubes being in communication at one end, and the burner-tube 115 in the roller being provided with a gas-supply pipe at its opposite end, and means for revolving said roller, and for raising the pressing-iron against the operation of the springs 120 by which it is depressed, consisting of a pulley mounted in said frame above said pressing-iron, a chain mounted thereon and connected with said iron, and a lever connected with the shaft of said pulley and operating in connection with a locking device secured to said 125 frame, substantially as shown and described.

In testimony that I claim the foregoing as my invention I have signed my name, in presence of the subscribing witnesses, this 12th day of August, 1897.

KATHARIN ELIZA LANDAU.
